JOHN MILLER, OF BUFFALO, NEW YORK.

Letters Patent No. 63,076, dated March 19, 1867.

IMPROVEMENT IN BUNGS FOR CASKS, BARRELS, &c.

The Schedule referred to in these Letters Patent and making part of the same.

TO ALL WHOM IT MAY CONCERN:

Be it known that I, JOHN MILLER, of the city of Buffalo, in the county of Erie, and State of New York, have invented an improved Bung or Stopper for Casks, Barrels, &c.; and I do hereby declare that the following is a full and exact description thereof, reference being had to the accompanying drawings, making part of this specification, in which—

Figure 1 is a central vertical section of my improvement, with the stopper or plug, B, of the bung driven down preparatory to being wedged up in its proper position.

Figure 2 is a similar section, that through the plug B being in a plane at right angles to the one in fig. 1, the bung being represented in place in a portion of a cask, and the parts thereof in the required position for closing the orifice.

Figure 3 is a plan of the bung detached.

Like letters of reference designate corresponding parts.

The object of my improvement is to provide a bung that shall be of the most durable nature, that may be readily inserted or removed from the cask or other vessel, and which shall form at all times a perfectly air-tight stopper, and be secure against the possibility of displacement from the pressure within.

The invention consists of a metallic box or lining which screws into the bung-hole, together with a plug of peculiar construction, and ring of suitable packing material, by which the orifice is closed; as hereinafter fully set forth.

In the drawings, A represents the box for lining the bung-hole, slightly tapering on the outside, and provided with a thread for screwing tightly in the orifice. It has a flange, c, at the outer end, which acts as a stop to prevent it from being accidentally screwed in too far, this flange having notches, d d, in its edge (shown most clearly in fig. 3,) for the points of the wrench in inserting or removing the box. The opening through this box is cylindrical till near the inner or lower end, where it is gradually enlarged, as shown at e, for a purpose presently to be explained. B is the main portion of the plug, in length about equal to the box A, the upper or outer portion being cylindrical, and of a diameter sufficiently small to allow adequate space for the packing, F, which surrounds it, while the lower portion, g, is enlarged so that its slides shall conform in direction, or nearly so, with those of the enlargement at the end of the box. There is a socket, j, formed in the upper end of the plug, into which screws a head, h, of a diameter a trifle less than that of the orifice of the box. A hole, i, elongated or formed with recesses on each side, is made, extending through this head into the socket j. K is a tool and handle for operating the plug, the lower end, l, being reduced in size, so as to enter the orifice in driving in the plug, as shown in fig. 1. To the end l is secured, in any suitable way, a short flattened rod, m, provided with lugs on each edge at the end, as shown in red lines, fig. 2. In operating with this tool, the point or extremity m is inserted in the hole i, in the head of the plug, till the face of l comes in contact with the latter, the lugs or ears at the end extending just below the end of the head, and into the socket j.

My improvement is employed in the following manner: The box A is first screwed into the orifice in the cask, when a ring or short section of India-rubber pipe, or equivalent elastic material for forming a packing, of about the relative length shown, is slipped on the cylindrical end of the plug B, and the head h screwed in. The plug is then driven in the box by means of the tool K, as above described, till the shoulder o strikes against the box, the parts being in the position shown in fig. 1. The handle K is now turned one-quarter around, so that the lugs at the end of m will catch under the end of the head h, when by drawing up on the handle, the lower and enlarged end of the plug distending the lower end of the packing, in the enlargement of the box, prevents it from sliding up in the latter, and thereby wedges and packs it firmly between the two, forming a perfectly secure and air-tight joint, the pressure of the gas evolved within the cask operating to pack the joint still more tightly, instead of loosening the bung, as in the ordinary construction employed. The lower end of the stopper may be formed with a narrow rim or flange, s, as shown, although its use is not very essential, as it simply gives the end of the plug an increased size, which might sometimes be necessary when the packing material is unusually soft and yielding. The bung-hole may be opened when required, by either unscrewing the box and removing the device entire, or the plug may be driven through into the vessel, from which it can be readily removed after the liquid has been drawn out, by unscrewing the box, which will leave an opening of

sufficient size for the purpose. The box A may be employed for lining the orifice when the ordinary wooden bung is used, in which case the hole in the vessel is protected from the wear to which they are usually subjected by the frequent insertion and removal of the bung, so that a vessel may be used a much longer time when provided with this protection. The aperture through the box being smooth and cylindrical, enables the same to be tightly closed with less difficulty, the strength of the metal allowing the plug to be driven in with great force, if required, without injury to the cask. My improved plug B is specially adapted for closing vessels that are required to be kept perfectly air-tight, and when they are to be subjected to a great pressure from the confined gases evolved within, for, as before stated, the greater the pressure the more perfect and tight the joint becomes, while the ordinary bung is frequently loosened or forced out by the internal pressure, or from that cause, and from the jarring to which the vessels are subjected during transportation.

What I claim as my invention, and desire to secure by Letters Patent, is—

1. The metallic box A, expanding inwardly to receive the plug B, when employed as a lining for bung-holes, and constructed substantially as described.
2. I also claim the plug B, when provided with the head h, and enlarged end g, and combined with the packing-ring F, and box A, substantially as set forth.
3. I also claim the handle and driver K, constructed and operating with the other parts as described.

In witness whereof I have hereunto signed my name in the presence of two subscribing witnesses.

JOHN MILLER.
